PERMANENT WAVE CLIP

James Edward Dwyer, New York, N. Y., assignor
to E. Frederics, Inc., New York, N. Y., a corpora-
tion of New York

Application October 23, 1937; Serial No. 170,526

10 Claims. (Cl. 132—33)

The invention relates to clips for use in hair waving and particularly to the type of clip which is adapted for use in the production of "permanent" waves.

5 Among the coiffures which hairdressers are called upon to produce are a number of styles which require the production of a wave or curl at only the end of the hair, that is, what is commonly referred to as "end curls". In creating this 10 sort of wave by methods employing the type of curlers or protector clips and heaters used prior to my invention there frequently occurred scalp burns or neck burns by reason of the loose arrangement of these devices in the hair. The 15 curlers or protector clips and heaters were secured to the hair three or four inches away from the scalp and no positive means were provided for holding them away from the head and neck. It is an object of the present invention to eliminate 20 this hazard by providing a clip of such a construction as to prevent the heating element from coming in contact with the scalp.

A further and more specific object of the invention is to provide a permanent wave clip 25 which has a supporting bracket adjustable to various positions in accordance with the length of the hair which is to be left uncurled and which makes it possible to secure a uniform curl around the head. Other objects and ad- 30 vantages will appear as the description proceeds.

In the drawing:

Fig. 1 is an end elevational view of a preferred embodiment of my novel wave clip illustrating the manner of application thereof.

35 Fig. 2 is a plan view of this same clip and Fig. 3 an elevational view thereof as seen from the right side of Fig. 2.

Figs. 4 and 5 are a plan view and elevational view respectively of another embodiment of the 40 invention in which a dual supporting bracket is provided.

Referring to Figs. 2 and 3 there is shown a clip comprising a pair of separable arms 1 and 2 hinged together at one end as at 3 and provided 45 at the other end with a locking device, indicated generally at 4, for holding the arms 1 and 2 tightly together after the hair has been drawn therebetween. The arms 1 and 2 are provided with suitable resilient coverings 1', 2'. At either 50 end of the arms 1 and 2 there are provided supporting members 5 and 6 adapted to support a curling rod of any desired form. Supporting member 6 is provided with a rotatable locking clip 7 for securing the curling rod in place.

55 Secured to the arm 1 is an adjustable support-

ing bracket comprising channel-shaped exten- 5 sions 8 and 9 in which are slidably arranged the legs 10 of a supporting bracket, the head bearing portion 11 of which preferably is provided with a pad 12 which may be of cork or other resilient heat-insulating material which will provide a cool and comfortable rest against the head. The arms 10 are provided with longitudinal slots 13 and rivets 14 pass freely through these slots and through apertures formed in the 10 extensions 8 and 9 to secure the legs 10 of the bearing member 11 to the extensions 8 and 9. The rivets 14 likewise extend through apertures in friction spring elements 15 which are held under tension by the rivets 14 against the legs 15 10 so that the bearing member 11 is held there- 20 by in any desired adjustment with respect to the clip. In Figs. 2 and 3 the bearing member 11 is shown in its fully extended position. The extension 9 is attached to the arm 1 of the clip 20 by means of a laterally-extending flange 16 which is riveted to the arm 1 at 17. A similar securing flange 18 is provided on the other ex- 25 tension 8, which also may be riveted to the arm 1 although I prefer that it be left free to permit the extension 8 to be swung out of the way so as to permit the removal of the resilient covering 1' from the arm 1 in the event that its replacement is desired. With this construction the flange 18 is held in place by the arm 1 and its resilient 30 covering 1'. At the ends of the bearing portion 11 of the supporting bracket there are provided extensions 19 which preferably are covered with a felted tape or other soft material.

In the embodiment illustrated in Figs. 4 and 5 35 the clip member with its arms 1 and 2 and other related structure is the same as has been described with reference to Figs. 2 and 3 but in place of the single adjustable supporting bracket there is provided a double bracket consisting of 40 two wire elements 20 having curved head bearing portions 21 and legs 22 the ends of which are bent over at 23 and pushed between the arms 1 and 2 and their respective resilient covering members 1' and 2'. The legs 22 preferably are 45 bent in the manner indicated in Fig. 5 so that the bearing portions 21 are separated to provide a wider supporting base for the clip.

In the application of my improved clip to the curling of the ends of the hair, the arms 1 and 2 50 are separated and a lock of hair drawn over the lower arm 1 in such a position as to leave the desired length of straight hair, as at 24 in Fig. 1. The second arm 2 is then brought down against the arm 1 and the two locked together by means 55

of the securing latch 4. If the supporting bracket 11 has not been adjusted previously to the correct position, it is now adjusted in such a way as to provide a support against the scalp or neck. 5 The ends of the hair which are to be curled are next wrapped around the curling rod, which is rolled into position in the supporting members 5 and 6 and locked by means of the rotatable clip 7. Such a curling rod is shown in position 10 in Fig. 1 at 25. If a ratchet type rod of the form known to workers in this art is employed, my adjustable supporting means may be used without clamping arms, the hair being held by the rod and the length of uncurled hair being 15 determined by the adjustment of the bracket.

It will be understood that various modifications may be made in the embodiments which I have described without departing from the claimed invention and I have no intention of 20 excluding such modifications or mechanical equivalents as may fall within the purview of the claims.

I claim:

1. A hair wave clip, comprising means for supporting a curling rod, means associated with said supporting means for clamping the supporting means to the hair, said clamping means provided with a supporting bracket having a bearing portion for contact with the scalp, said bearing portion being arranged in spaced relationship to said clamping means for maintaining said clamping means away from the scalp. 25

2. A hair wave clip, comprising means for supporting a curling rod, means associated with 30 said supporting means for clamping the supporting means to the hair, said clamping means provided with an adjustable supporting bracket to provide a bearing against the scale.

3. A hair wave clip, comprising means for supporting a curling rod, means associated with 40 said supporting means for clamping the supporting means to the hair, said clamping means comprising lateral extensions and a bearing member provided with legs cooperating with said extensions to provide adjustment of the bearing member with respect to the clamping means. 45

4. A hair wave clip, comprising means for supporting a curling rod, means associated with 50 said supporting means for clamping the supporting means to the hair, said clamping means comprising lateral extensions, a bearing member

having legs cooperating with said extensions and slidably with respect thereto, and a friction spring secured to said extensions and bearing against said legs to hold said bearing member in adjusted relationship to said clamping means. 5

5. A hair wave clip comprising means for supporting a curling element, a pair of separable clamping arms associated with said supporting means for securing the supporting means to the hair, said clamping arms provided with a supporting bracket to provide a bearing against the scalp. 10

6. A hair wave clip comprising means for supporting a curling element, a pair of separable clamping arms associated with said supporting 15 means for securing the supporting means to the hair, said clamping arms provided with an adjustable supporting bracket to provide a bearing against the scalp.

7. A hair wave clip comprising means for supporting a curling element, a pair of clamping arms associated with said supporting means for securing the supporting means to the hair, one of said arms having channel-shaped lateral extensions, a scalp bearing member, said bearing 25 member having legs slidably engaging said channel-shaped extensions, said legs having longitudinal slots therein, and securing means extending through said extensions and said slots for holding said bearing member in adjusted relation to said clamping arms. 30

8. A hair wave clip comprising means for supporting a curling rod, a pair of separable arms associated with said supporting means for securing the supporting means to the hair, each of 35 said arms having a supporting bracket secured thereto.

9. A hair wave clip comprising means for supporting a curling rod, a pair of separable arms associated with said supporting means for securing the supporting means to the hair, each 40 of said arms having a supporting bracket removably secured thereto.

10. Hair waving apparatus comprising a curling rod, means supporting said rod for rotation, 45 said supporting means including a bracket for maintaining said rod a predetermined distance from the scalp, and means associated with said supporting means for maintaining taut the hair between the scalp and said curling rod. 50

JAMES EDWARD DWYER.
